NOSE GUARD

Filed Aug. 14, 1929

L.C. Medearis, Inventor
By *C. Snow & Co.* Attorneys.

UNITED STATES PATENT OFFICE

LORAIN C. MEDEARIS, OF STORM LAKE, IOWA

NOSE GUARD

Application filed August 14, 1929. Serial No. 385,725.

This invention relates to a nose guard for use on horses to prevent them from eating vegetation while working in fields and for use as a muzzle, and to prevent said animals from being annoyed by the bite of insects.

It is an object of the invention to provide a guard having a clear portion that will supply air more freely to the animal than has heretofore been possible where guards of the basket type have been used.

With the foregoing and other objects in view which will appear as the description proceeds the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

In said drawings,

Figure 1 is a plan view of the guard.

Figure 2 is a view looking into the open end thereof.

Figure 3 is a section on line 3—3, Figure 1.

Referring to the figures by characters of reference, 1 designates a stiff wire ring to which is attached the edge portion of a semi-ellipsoidal basket-like structure 2 formed of a wire fabric. Ring 1 and the edge portion of the fabric have a strip of fabric or other suitable protecting material embracing the same as indicated at 3, this material being attached to the fabric by sewing or in any other manner desired.

A portion of the wire fabric structure 2 is cut away from the ring 1 toward the center of the guard, thereby to provide a clear space 4.

The edges of this opening are embraced by a strip 5 of leather or fabric constituting a protecting medium.

Reinforcing wires 6 are fitted snugly against the inner surface of the wire fabric and have their ends bent outwardly and pressed tightly into engagement with the strip 3. These outturned ends of the wires have been indicated at 7 and serve to firmly anchor the wires within the guard. The wires

are offset at their points of crossing and interwoven, as shown at 8 so that they will not shift relative to each other after they have been assembled properly. One of the wires may be extended along the center of the opening 4.

Wire loops 9 may be pivotally connected to the wire 1 at diametrically opposed points equidistant from the opening 4 and these are adapted to be engaged by straps or the like used for holding the guard on the nose of the horse. When the guard is thus positioned the nostrils will be exposed through the opening 4 so as to permit unobstructed breathing.

What is claimed is:

A combined nose guard and insect excluder including a semi-ellipsoidal basket-like structure of closely woven wire fabric, a reinforcing ring connected to the fabric and extending around the large end of the structure, there being a segmental opening in the fabric closed at its upper end by the ring, relatively soft protecting strips extending along the ring and those edges of the fabric defining the opening, said protecting strips constituting means for snugly engaging the head of an animal to which the guard is applied, thereby to prevent admission of insects into the guard, and reinforcing wires bowed longitudinally and having their ends gripped upon the ring, said wires being taut and being held against relative movement by having interwoven portions adjacent to the center of the fabric, two of the wires constituting reinforcements for the sides of the opening in the fabric and being covered by a portion of a protecting strip.

In testimony that I claim the foregoing as my own, I have hereto affixed my signature.

LORAIN C. MEDEARIS.
